US00D731211S

(12) **United States Design Patent**
Denby et al.

(10) **Patent No.:** **US D731,211 S**
(b4) **Date of Patent:** ** **Jun. 9, 2015**

(54) **VITRINE**

(75) Inventors: **Scott E. Denby**, Minneapolis, MN (US); **Jason W. Johnson**, Wayzata, MN (US); **Timothy J. Martell**, Brooklyn Park, MN (US); **Joseph R. Stukenberg**, Minneapolis, MN (US); **Daniel J. Noll**, Madison, WI (US)

(73) Assignee: **Target Brands, Inc.**, Minneapolis, MN (US)

(**) Term: **14 Years**

(21) Appl. No.: **29/427,357**

(22) Filed: **Jul. 17, 2012**

(51) **LOC (10) Cl.** **06-04**

(52) **U.S. Cl.**

USPC **D6/672; D6/675**

(58) **Field of Classification Search**

(57) **CLAIM**

The ornamental design for a vitrine, as shown and described.

DESCRIPTION

FIG. 1 is a perspective view of a vitrine;

FIG. 2 is a top view thereof;

FIG. 3 is a bottom view thereof;

FIG. 4 is a front view thereof, the back view being identical;

FIG. 5 is a side view thereof, the opposing side being identical;

FIG. 6 is a section view thereof; and,

FIG. 7 is an enlarged view of a portion of the section view illustrated in FIG. 6.

The broken lines are included for purposes of illustrating portions of the vitrine and form no part of the claimed design.

1 Claim, 4 Drawing Sheets
